INTERCHANGEABLE LETTER SIGN

Jack W. E. Simpson, Richmond, Va.

Application April 12, 1949, Serial No. 87,092

1 Claim. (Cl. 40—143)

1

This invention relates to a sign and supporting means therefor and a method of locating and mounting the same.

Three dimensional signs have come into quite general use in recent years because of their obvious impressive and striking appearance as distinguished from conventional signs painted on flat surfaces. These signs have been largely of two general types, namely, track mounted and free standing. The former embodies supporting tracks or brackets extending throughout the length of the sign to which the individual letters or other characters are secured. These tracks can be readily mounted horizontally or in other desired positions according to the nature of the sign and simplify the mounting and supporting of the letters or other characters. The tracks, of course, are visible, and are inclined to detract somewhat from the sign as well as to add to the cost thereof.

Free standing signs, of course, are capable of use only where there is a supporting ledge or other surface over which the sign characters may be arranged. The proper alignment and general arrangement of the sign characters also involves no particular problem in free standing signs, it being relatively easy, for example, to support all of the sign characters the same distance above a horizontal ledge so that the characters are properly aligned.

The use of individually mounted sign characters is highly desirable for two reasons. In the first place, the supporting means therefor can be made substantially invisible, thus adding to the attractiveness of the sign. In the second place, the supporting devices for individually supported sign characters are cheaper to manufacture and easier to handle than the supporting means for track mounted signs. However, the use of individually supported sign characters introduces a substantial difficulty in the proper locating of the sign characters, it being necessary to individually locate each sign character, which cannot readily be done by the average mechanic.

An important object of the present invention is to provide a novel third type of three dimensional sign, namely, individually mounted sign characters, each of which has its own supporting means associated therewith.

A further object is to provide a highly simplified type of sign or sign character supporting means which may be quickly and economically placed in position and wherein the sign characters are readily removable for the purpose of

2

painting or cleaning the sign characters or the surface over which they are arranged.

A further object is to provide such a mounting wherein individual mounting elements are employed, the location of which may be accurately spotted by the use of a simple template.

A further object is to provide a novel sign character mounting of the type referred to wherein the dislodgement of the sign characters is prevented while at the same time permitting easy removal of the characters.

A further object is to provide a novel method of laying out the arrangement of the characters of a sign relative to each other to facilitate the application of the sign adjacent the surface with respect to which it is to be supported.

A further object is to provide a novel method of the character referred to wherein a template for determining the mounting of the sign characters may be shipped along with the latter and the supporting means therefor, and wherein the template readily may be temporarily fixed against the sign supporting surface to locate the points of connection of the sign supporting elements relative to such surface.

Other objects and advantages of the invention and the method referred to will become apparent during the course of the following description.

In the drawing, I have shown one embodiment of the invention and the method for practicing the invention. In this showing,

Figure 1 is a perspective view of a sign character and supporting means therefor shown in its mounted position with respect to a supporting surface.

Figure 2 is a sectional view taken vertically parallel to and just rearwardly of the sign character, the latter being shown in construction lines.

Figure 3 is a detailed sectional view on line 3—3 of Figure 2.

Figure 4 is a detailed perspective view of one of the hangers.

Figure 5 is a detailed perspective view of a template adapted for use with the particular character shown in Figures 1 and 2 for spotting the supporting means.

Figure 6 is a plan view of a work table showing one step in the method of laying out the complete sign template.

Figure 7 is a similar view showing the template completed.

Figure 8 is a face view of the sign template arranged in position on the sign supporting surface, a sign to be mounted being indicated in broken lines on the template, and

Figure 9 is an end elevation of the work table showing the sign template and an individual character template in working position thereon.

Referring to Figure 1, the numeral 10 designates a sign character shown in the present instance as the letter "R." It will be obvious, of course, that the mounting means described below is applicable to any letter, number, or other sign character. In accordance with conventional practice in this type of sign, the characters are relatively thick and preferably formed of a series of wood laminations 11 (Figure 3), the letters being cut from plywood having waterproof bonding between the laminations. Obviously, the characters may be made of plastic or any other suitable material.

At a plurality of spaced points on the back face of each character is arranged a plurality of hangers 12, the number and location of which depend upon the character to be supported. In the present instance, three of the hangers are employed, one adjacent the top and two adjacent the bottom of the character, located preferably as shown in Figure 2. Each hanger comprises a shank 13 having a threaded end 14, and a collar 15 is engageable against the rear face of the character to limit the threaded depth of penetration of the threaded ends 14 into the character so that the downturned inner ends 16 on each hanger will lie in a common vertical plane parallel to the plane of the rear face of the character.

Each downturned end 16 is adapted for insertion in an opening 18 formed in the horizontal arm of a small angular supporting bracket 19. The vertical arm of each bracket is apertured as at 20 for the insertion of a wood screw 21 or any other suitable securing element.

Each depending end 16 has its lower extremity rounded as at 24 and vertically split as at 25. The purpose of this construction will be referred to later.

The supporting means for the sign characters is extremely simple in construction and economical to manufacture, and the supporting elements for each letter may be located relative to each other very easily in accordance with the practice of the present method. A simple template is used for each individual character, and in Figure 5, I have illustrated a single character template in the form of the letter "R," corresponding to the letter shown in Figures 1 and 2, and this template has been indicated by the numeral 26. The template conveniently may be made of any suitable preferably thin material and corresponds in shape to a particular character, in the present instance the letter "R" as stated. Each template is provided preferably with an upper opening 27 and a pair of lower openings 28 corresponding in position to the desired location of the shanks 13 of the hangers 12, and also corresponding in arrangement to the desired locations of the fastening elements 21, as further described below. It will be obvious that each individual character is provided with a corresponding template, and the number and arrangement of the openings in each template will depend upon the type and size of each character. At least three openings are employed to locate at least three hangers for each character, to rigidly fix each sign character in position against relative movement in the finished sign.

The present invention facilitates the manufacture of finished signs at the factory and the shipment of the characters to a local installation concern as packaged units. The method contem-

plates the inclusion in such package of a template through the use of which the completed sign may be quickly and accurately placed in position. In this connection, it is pointed out that in mounting the letters of a sign of this character, it is necessary that the letters be properly aligned, properly individually placed, and properly spaced. The proper spacing of letters involves particular difficulty to a worker not skilled in this particular field, and it is also difficult for him to center the sign with respect to a surface of a given width. The present invention eliminates all difficulties of this character involved in the erection of the sign.

Referring to Figure 6, the numeral 32 designates a work table of substantial length on the top of which is fixed a positioning guide 33 having a horizontal flange 34 fixed to the top of the work table. The positioning guide further includes an inwardly extending horizontal flange 35 spaced slightly above the surface of the table as clearly shown in Figure 9.

A sign template 38 of flexible material such as heavy paper is arranged on the table top in the manner shown in Figures 6, 7 and 9. The material for the sign template may be in roll form and a sufficient length of the material is unrolled, according to the approximate length of the sign, the strip torn from the roll preferably being substantially longer than necessary. This sheet is arranged on the table top and one edge is slid beneath the flange 35. The free edge 39 of the positioning guide is straight and accordingly forms a straight edge for locating the bottom edges of the sign characters. In general, it may be stated that the total length of a sign, in inches, will be the product of the height of the sign letters in inches and the number of letters in the sign. The sign outlined in Figure 6 contains five letters and assuming that the letters are six inches in height, the total length of the sign will be approximately thirty inches. This length, or any other length in accordance with particular conditions, having been determined, the template 38 will be marked with two vertical lines 40 and 41. The character template 26 for the first letter of the sign, "R" in this case, will be arranged with its left hand edge coincident with the line 40. A template 26 for the last letter, "O" in this case, will be arranged with its right hand limit coincident with the line 41. These templates will be vertically arranged with the bottoms thereof in contact with the edge 39, and the remaining templates 26 will be placed in position by a skilled sign mechanic with the proper spacing between the letters. These letters or other characters having been located, a suitable implement will be employed for punching openings 42 (Figure 7) in the template sheet 38. After all of these openings have been punched for a given sign, the template is completed and ready for use.

The individual templates are placed in registering position against the back faces of the individual character 10, and marks are placed on the backs of the characters through the openings 27 and 28 to locate the centers for the shanks 13 of the hangers. Preferably, these marks are made with a pointed instrument to provide an indentation sufficiently deep to start the threads 14 when the hangers 12 are to be attached to the characters. The hangers 12 may be attached to the characters at the factory, but preferably are placed in a bag or separate package to be shipped in the package or box with the characters to make up the complete sign. In this way, the characters will not require nearly as much space

and the resultant package will be smaller and capable of shipment at a minimum freight rate.

In the package or box in which shipment is made, there will be included brackets 19 and fastening elements 21 at least equal in number to the number of hangers 12 to be used on the sign.

The package also will include the complete template 38, and the package as thus received by the local installer will contain everything necessary for completing the sign.

The package may be directly carried by the installer to the building on which the sign is to be placed. The complete template 38 will be placed against the surface to carry the sign, for example against the brick wall indicated in Figure 8 by the numeral 45. The top or bottom edge of the complete template may be lined up with a horizontal mortar joint of a brick or similar masonry wall, or it may be otherwise arranged level if the sign is to be horizontal. The space between the lines 40 and 41 is then centered with respect to the space which is to carry the sign, or otherwise horizontally located. The complete template is then supported in position by any suitable means, and most conveniently by strips 46 of adhesive tape, as shown in Figure 8. A punch then may be used through each of the openings 42 to locate the centers to receive the fastening elements 21 for the brackets. In the case of a masonry wall, it will be necessary to use a suitable implement such as a stone drill to drill openings corresponding in position to the openings 42. These openings may be drilled with respect to all of the individual openings 42 before removing the complete template 38, or the positions of the openings may be marked with a center punch, whereupon the template 38 may be removed and openings drilled at the marked points. Where the sign is to be attached to a wood surface, it merely will be necessary to mark the surface through each opening 42, whereupon the template 38 may be pulled from the supporting surface.

As a result of the foregoing step, the surface to support the sign will bear a mark or opening to receive each of the fastening elements 21. It is not even necessary for the operator to bear in mind what sign characters are to be placed in position, it merely being necessary for him to apply a fastening element 21 through the aperture 20 of a bracket 19 and screw or otherwise secure the fastening element to the supporting structure at each mark. When this has been done, there will be a bracket arranged exactly in the correct location to receive a depending end of a hanger 12 secured to the proper letter.

It will be apparent that the marks, dents, or openings made in the back faces of the letters at the factory will exactly coincide in arrangement with the openings marked by means of the template 38. An operator will then attach one of the hangers to each of the marks on each letter, whereupon the sign is ready for assembly. In the present case, the three hangers attached to the letter "R" will exactly coincide with the first three marked openings in the supporting structure, starting from the left in Figure 8. The operator will merely place the lower extremities of the depending ends 16 of the hangers for the letter "R" over the apertures 18 of the corresponding brackets and move the letter directly downwardly. Each hanger will then engage its bracket as shown in Figure 3. The same procedure is followed for each of the letters and regardless of the positions of the hangers on each

letter, the proper brackets will be correctly placed to receive the depending ends of the hangers.

Thus it will be apparent that practically all measurements are eliminated from the work of the installer, it merely being necessary to place the template 38 as a single entity in the proper position on the supporting surface. Regardless of the number of letters or characters on the sign, the exact location for the brackets 19 will be readily determinable without any skill on the part of the installer. Obviously, the letters of the sign need not be horizontally arranged, nor need the sign be limited to a single line of letters or characters. Almost without regard to the type of sign, a single template 38 serves to locate all of the component parts of the sign. If desired, of course, a sheet template 38 may be used for each individual word of any other group of characters forming part of the finished sign. The present invention thus renders it practicable to make any sign complete at a central factory and to ship it as a packaged unit with all of the articles necessary for the complete location and erection of the sign by relatively unskilled labor, it being unnecessary for the installer to understand anything about the arranging of the sign elements in order to perform a perfect job of installation. The present invention thus permits the economical manufacture of signs at a central plant on a real production basis, thus permitting the effecting of economies in manufacture. Moreover, the simple elements employed for supporting the characters likewise facilitate economical manufacture, and the supporting elements being arranged rearwardly of the sign characters permit the use of a sign in which the supporting means is substantially invisible.

It requires a direct lifting force to remove any letter or character from its supporting means. To positively prevent accidental dislodgement, the split ends of the hangers are spread slightly as shown in Figure 2 so that the lower extremities of the ends 16 are slightly larger in one transverse dimension than the diameter of each opening 18. Thus the sign characters are positively prevented from becoming accidentally dislodged.

However, if it is desired to remove the sign characters, for example for the purpose of repainting them or painting the supporting surface over which they are arranged, a reasonable exertion of upward force will dislodge each sign character. The characters are readily replaceable in the manner previously described, the rounding of the extremities of the depending ends 16 facilitating the insertion of the ends 16 in the apertures 18 of the brackets.

I claim:

In a sign including a three dimensional character formed of penetrable material, the improvement comprising a plurality of hangers fixed to the rear side of said character, each hanger having a horizontal threaded end threaded into said character from the rear side thereof, a collar spaced from such end to each hanger to limit the depth of penetration of said threaded end into said character, each hanger having its opposite end depending substantially vertically at a point spaced from said collar, the distance from the collar to the depending end of each hanger being identical whereby, when all of said hangers are threaded into said character with the collars thereof contacting with the rear face of said character, all of said depending ends will lie in a single vertical plane, and brackets

corresponding in number and arrangement to said hangers and secured against the supporting structure, each bracket having a horizontal portion provided with a vertical opening to receive the depending end of one of said hangers, each such depending end being split to be spread to prevent upward displacement of said character except by the use of force, and each such depending end being rounded at its lower extremity whereby, after said depending ends have been removed from said openings, said rounded ends while seated in said openings, upon the applica-

tion of downward vertical force, will contract said split ends for re-insertion in said openings.

JACK W. E. SIMPSON.
